By Atty. N. Dubois.

UNITED STATES PATENT OFFICE.

JOSEPH A. BAKER, OF CHICAGO, ILLINOIS.

DESIGN FOR A LAWN-MOWER WHEEL.

SPECIFICATION forming part of Design No. 31,944, dated December 5, 1899.

Application filed November 2, 1899. Serial No. 735,644. Term of patent 14 years.

To all whom it may concern:

Be it known that I, JOSEPH A. BAKER, a citizen of the United States, residing at Chicago, in the county of Cook and State of Illinois, have by my own industry, genius, efforts, and expense invented and produced a new, useful, and original shape or configuration of an article of manufacture—to wit, Lawn-Mower Wheels—of which the following is a specification, reference being had to the accompanying drawings, forming part hereof.

My design relates to the main supporting-wheels or drive-wheels of lawn-mowers of that class which are of such form as to prevent the flat surface or tread of the wheel from crushing the uncut grass over which the wheel travels; and my design resides and is embodied in the peculiar form and configuration of the wheel as a definite article of manufacture, as hereinafter set forth.

Referring to the drawings, Figure 1 is a side elevation, and Fig. 2 is a top plan view, of a wheel embodying my said design.

The main or body portion of the wheel is cylindrical. Disposed around the periphery of the wheel are radial projections in approximately the form of truncated cones. These projections are arranged in rows, the projections in one row being opposite and approximately central to the spaces between contiguous teeth in the other row, substantially as shown in the drawings.

That which I have invented and produced and that which I desire to secure by Letters Patent is—

The design for a lawn-mower wheel as herein shown and described.

In witness whereof I have hereunto subscribed my name, at Chicago, Illinois, this 17th day of October, 1899.

JOSEPH A. BAKER.
